UNITED STATES PATENT OFFICE.

GEORGE A. WASHBURN, OF CLEVELAND, OHIO, ASSIGNOR TO FORD & WASHBURN, OF SAME PLACE.

SECONDARY BATTERY.

SPECIFICATION forming part of Letters Patent No. 451,541, dated May 5, 1891.

Application filed October 24, 1890. Serial No. 369,181. (No model.)

To all whom it may concern:

Be it known that I, GEORGE A. WASHBURN, a citizen of the United States, residing at Cleveland, in the county of Cuyahoga and State of Ohio, have invented certain new and useful Improvements in Storage-Batteries; and I do hereby declare that the following is a full, clear, and exact description of the invention, which will enable others skilled in the art to which it appertains to make and use the same.

My invention relates to storage-batteries, and is an improvement in the form of battery shown and described in my application, Serial No. 359,666, filed July 23, 1890.

In the accompanying drawings, Figure 1 is a plan view, partly sectioned horizontally at the right, of a battery-cell containing my improvements. Fig. 2 is a perspective view of the cell with one side and end removed to disclose the internal construction. Fig. 3 is a cross-section of an inclosing case with two compartments having two separate cells, and showing the cell materials in position.

As stated in the application upon which this invention is an improvement, the cell consists in an outside containing-vessel A, of hard rubber, glass, or other suitable material, a cup B, of lead or other conducting material forming a lining for the receptacle, and an inner perforated conducting-plate C, set a suitable distance from the cup B, so that active material may be placed between said cup and plate.

D represents a porous cup, E a series of perforated conducting-tubes open at their bottom and top, and F an inside perforated-tube open at both ends, oblong in cross-section, so as to have flat sides opposite the tubes E.

In this construction of battery the positive electrode is preferably arranged within the porous cup, and, inasmuch as there is a tendency in the positive electrode to grow or expand more or less, I have found it necessary, in order to protect the porous cup from being sprung open or broken by such expansion, to so construct the conducting-plates that they will accommodate themselves to whatever expansion may occur, and thus save the cup. This is accomplished by making either the in-

side tube F alone in such a form that it will accommodate the lateral pressure exerted by the material in expansion or by making the tubes E to take up the expansion, or by constructing both with a view to the same result. 55 Ordinarily in a cup oblong in cross-section, substantially as here shown, the inner tube F with flat sides alone serves the purpose of relieving the pressure, the dotted lines showing the position which the said tube may assume when acted upon by the lateral pressure in the cup or pot. Said tube may be made whole, as shown in the drawings, or it may be formed in a single piece with overlapping free edges, or it may be made in parts or pieces 60 which overlap. The tubes E are shown here as having overlapping free edges d, so that they likewise will accommodate themselves somewhat to the expansion of the material within the porous cup; but they may be made 65 whole.

The invention which I desire to cover consists in so forming the conducting-plates, whatever shape they may be made or assume, that when arranged within the porous cup 75 they will, by reason of their construction, accommodate themselves to any expansion of the material that may occur, and thus preserve the cup intact, while at the same time they form open spaces within themselves for 80 the battery-liquid. The active material is placed between the tubes E and the cup D and the central tube F, while the said tubes themselves are filled with liquid. These tubes are liberally perforated, as shown in Fig. 2, 85 so that there is the utmost exposure of the active material to the liquid and that freedom of circulation through the cell which is deemed necessary to the perfect working and highest efficiency of the battery.

I do not wish to be considered as limiting myself to any special material forming the tubes E and F or to any special form of said tubes or parts. For greater economy and efficiency of the battery these tubes or conductors are constructed of material which will be in sympathy with the active material in its work—such, for example, as lead or the like.

The battery thus constructed is coupled up in the usual way, the tubes or their equiva-

lent within the porous cup forming the conductors for the inner electrode, and the lining B and the inner wall or plate C forming the conductors for the outer electrode, and either 5 may be positive or negative, as may be deemed best, although I prefer to make the inner electrode the positive one.

In Fig. 3 I show an arrangement of two 10 cups constructed on this principle, contained in a double-compartment receptacle.

It will be understood that the space between the porous cup and the plate or wall C is filled with solution which of course, will readily work through the porous cup into contact with 15 the active material in said cup.

In the event a round cylindrical porous pot 20 be used the compressible tube or tubes will be constructed to adapt them to that form of cup, which may be by overlapping edges or 25 in any other suitable manner.

Having thus described my invention, what I claim as new, and desire to secure by Letters Patent, is—

1. In a storage-battery cell, a porous pot 25 containing active material and conductors in the pot constructed to form an open space in the pot for solution and to yield under lateral

pressure or expansion, substantially as described.

2. A storage-battery cell containing a porous cup, conductors in said cell constructed to be more or less compressed by the expansion of the active material, and active material in said cup about said conductors, substantially as described. 30

3. In a storage-battery, a porous cup, a compressible tube or tubes of conducting material in the cup, and active material about the tube or tubes, in combination with an electrode outside said cup and solution within and without the cup, substantially as described. 35

4. In a storage-battery, a porous cup containing hollow compressible conductors, in combination with an electrode outside of the cup, formed of opposed conducting-plates, and active material between said plates and in the porous cup, substantially as described. 40 45

Witness my hand to the foregoing specification this 20th day of October, 1890.

GEORGE A. WASHBURN.
